FRICTION DEVICE FOR FILLING CARRIERS

Carl A. Anderson, Putnam, Conn., assignor to
Guaranteed Parts, Inc., Allston, Mass., a cor-
poration of Massachusetts

Application April 30, 1934, Serial No. 723,118

3 Claims. (Cl. 139—251)

This invention relates to a friction device for filling carriers, particularly that carrier located in a rotary hopper for carriers, which is located in transferring position and is next to be transferred to the shuttle.

The object of the invention is to provide a simple effective device for engaging the filling carrier which is located in transferring position and creating sufficient pressure thereon to prevent said carrier from rotating in the hopper as a consequence of the vibration of the latter, to the end that the filling will not unwind from the carrier and be subjected to the danger of breaking during the subsequent operation of the shuttle after the carrier has been transferred thereto.

Another object of the invention is to embody in the device a friction element of a character which will yield upon engagement with the filling to conform slightly to irregularities upon the surface of the filling and which will not cause injury to the filling because of its engagement therewith.

Still another object of the invention is to so construct the friction device that it will also constitute an effective means for aiding in supporting the filling carrier mentioned, while said carrier is located in transferring position.

The invention consists in a friction device for filling carriers as set forth in the following specification and particularly as pointed out in the claims thereof.

Referring to the drawing:—

Fig. 1 represents a vertical sectional elevation of portions of a filling replenishing loom including a lay having a shuttle mounted thereon, a hopper for filling carriers and a transerrer mechanism for said carriers, a friction device for filling carriers embodying my invention being illustrated associated therewith.

Fig. 2 is a plan view partly broken away and illustrated in section of a portion of the mechanism illustrated in Fig. 1 and including the friction device of this invention.

Fig. 3 is a perspective view of the friction device.

Like numerals refer to like parts throughout the several views of the drawing.

In the drawing, 5 represents a portion of the frame of a filling replenishing loom, 6 a lay, 7 a shuttle box and 8 a shuttle positioned in said box. Mounted upon the frame 5 is a stand 9 for a rotary bobbin disc 10 constituting a portion of a hopper 11 in which a plurality of bobbins 12 constituting filling carriers are mounted in a well-known manner. Mounted on the stand 9 is a

fixed transerrer stud 13 upon which is pivotally mounted a transerrer 14 provided with a downwardly projecting arm 15 to which a transerrer dog 16 is pivotally attached at 17. The dog 16 is adapted to be engaged by a bunter 18 mounted on the lay 6 to effect the operation of the transerrer 14 in a well-known manner and cause a bobbin 12 which is located in transferring position in the hopper 11 to be forced downwardly from said hopper into the shuttle 8.

All of the parts hereinbefore mentioned are old and their operation is well known in the art. It is also well known that portions of this mechanism, particularly the hopper 11, are caused to vibrate excessively with the result that there is a tendency for the filling carriers 12 to rotate upon the portions of the hopper upon which they are mounted, thereby causing the filling to unwind. When this happens it is a common occurrence after the filling carrier has been transferred to the shuttle for the filling thread to break when the shuttle is driven across the lay with the result that the loom is caused to stop and production therefore is stopped until the loom is again started.

The friction device of this invention is mounted upon an arm 19 which is rigidly fastened to the transerrer stud 13 by a set screw 20. A finger 22 constituting a top holder is rigidly secured in any suitable manner to a pivot member 21 which is mounted to rotate in a bearing provided at the outer extremity of the arm 19. Mounted upon the opposite end portion of the pivot member 21 from that upon which the top holder 22 is mounted is a friction device 23 embodying therein a sleeve portion 24 which is secured to the pivot member 21 by a cotter pin 25 and said sleeve portion 24 therefore rotates in unison with said pivot member. The sleeve portion 24 is recessed at 26 to provide a space for receiving a coil spring 27 surrounding the pivot member 21 and one extremity of said spring is connected to the arm 19 and the other extremity to the sleeve 24 in a manner to cause the top holder 22 to engage a stop 32 provided upon the arm 19 at which time the top holder will be located in a position to support the small end portion of the filling carrier 12 when said carrier is located in transferring position.

Projecting laterally from the periphery of the sleeve portion 24 of the friction device 23 is an arm 28 provided with a groove 29 therein in which a friction member 30 is tightly gripped between the opposite jaw portions of the arm 28. The friction member 30 is constructed of flexible re-

- 5 silent material as, for example, rubber, or a material having the characteristics of rubber, and is provided with a beveled surface 31 which is adapted to underlie a filling carrier 12 which is located in transferring position and yieldingly engage the filling thereon in a manner to prevent the carrier from rotating in the hopper 11. The friction member 30 will furthermore act to aid in supporting the carrier with which it contacts.
- 10 It is desirable that the material of which the friction member 30 is constructed shall be sufficiently flexible to conform slightly to the contour of the surface of the filling with which said member contacts to the end that said member will effectively grip the filling material and thereby prevent the carrier from rotating without injuring the filling.
- 15

It will be understood that the arm 19, pivot member 21, top holder 22, sleeve portion 24 and spring 27 are all old and well known in the art and that the top holder 22 tips downwardly to release the carrier 12 every time a transfer is made. Applicant has utilized the pivot member 21 as a support for his improved friction device 23 and has redesigned the sleeve portion 24 to include the gripping means 28 for the friction member 30.

20 In the operation of the loom as the hopper 11 is rotated to successively position the filling carriers 12 into transferring position, the surface of the filling of the carrier next to be transferred will engage the bevelled surface 31 of the friction member 30 and the latter will yield slightly and engage the filling with a gentle flexing contact which will prevent the carrier from rotating and at the same time not injure the filling during the interval that the carrier is located in transferring position and at the time that the carrier is transferred to the shuttle. When the transfer is made the friction device 23 will rock in unison with the top holder 22 as the latter releases the carrier, and said friction device will act to guide the carrier during its transfer from the hopper to the shuttle.

I claim:

1. In a filling replenishing loom the combination of a rotary hopper for filling carriers, a trans- 5 ferrer stud, an arm fast to said stud, and a flexible friction member pivotally mounted upon said arm and adapted to yieldingly engage the filling on a carrier next to be transferred, said member having a material embodied therein having the characteristics of rubber and adapted to create a friction upon the carrier acting to prevent the rotation of the latter in said hopper, said friction member also constituting a support and guide for the carrier during its transfer from the hopper to the shuttle.

2. In a filling replenishing loom the combination of a rotary hopper for filling carriers, a trans- 15 ferrer stud, an arm fast to said stud, and a flexible friction member pivotally mounted upon said arm and adapted to tip downwardly thereon with each transferring operation, said friction member 20 having a yieldable inclined friction surface embodied therein adapted to underlie and support the carrier next to be transferred and create a friction upon the filling wound therearound thereby preventing the rotation of said carrier in 25 said hopper, said friction member also acting to guide the carrier during its transfer from the hopper to the shuttle.

3. In a filling replenishing loom the combination of a rotary hopper for filling carriers, a trans- 30 ferrer stud, an arm fast to said stud, a sleeve pivotally mounted upon said arm and having gripping jaws embodied therein, and a flexible friction member positioned between said jaws and having a yieldable friction surface embodied 35 therein adapted to engage the filling on a carrier next to be transferred from said hopper to a shuttle located therebeneath and create a friction upon the filling acting to prevent the rotation of said carrier in the hopper and to support 40 and guide the carrier during the transfer.

CARL A. ANDERSON.
